BEAUTICIAN'S STAND

Robert M. Farwick, 854 W. North Bend Ave.,
Cincinnati, Ohio 45244

Filed Nov. 27, 1968, Ser. No. 14,708

Term of patent 14 years

Int. Cl. D28—03

U.S. Cl. D86—10

Fig. 1

Fig. 2

FIG. 1 is a front perspective view of a beautician's stand showing my new design;

FIG. 2 is a top plan view thereof, the hose portion being shown broken away for convenience of illustration;

FIG. 3 is a side elevational view thereof, the hose and standard portions being shown broken away;

FIG. 4 is a side elevational view of the side opposite thereto, the hose, standard, and base being shown broken away for convenience of illustration;

FIG. 5 is a rear elevational view thereof; and

FIG. 6 is a bottom plan view.

I claim:

The ornamental design for a beautician's stand, substantially as shown and described.
